[57] **CLAIM**

The ornamental design for a combination foldable ruler and level, as shown and described.

DESCRIPTION

FIG. 1 is a perspective view of a combination foldable ruler and level showing my new design;

FIG. 2 is a perspective view, shown in an expanded condition of use;

FIG. 3 is a top plan view;

FIG. 4 is a bottom plan view;

FIG. 5 is another top plan view;

FIG. 6 is a side elevational view, the opposite side elevational view being a mirror image;

FIG. 7 is a right side elevational view; and,

FIG. 8 is a left side elevational view thereof.

FIGS. 1 and 2 have been drawn on an enlarged scale with respect to FIGS. 3-8.

FIG. 1

FIG. 2

FIG. 3

FIG. 4

FIG. 5

FIG. 6

FIG. 7

FIG. 8
